UNITED STATES PATENT OFFICE

96,727

DESIGN FOR A COMBINATION BRASSIÈRE AND SKIRT

Walter H. Deiches, New York, N. Y., assignor to Bloomingdale Bros. Inc., New York, N. Y., a corporation of New York

Application May 24, 1935, Serial No. 57,009

Term of patent 3½ years

To all whom it may concern:

Be it known that I, Walter H. Deiches, a citizen of the United States, residing at New York, in the county of New York and State of New York, have invented a new, original, and ornamental Design for a Combination Brassière and Skirt, of which the following is a specification, reference being had to the accompanying drawing, forming part thereof.

I claim:

The ornamental design for a combination brassière and skirt, as shown.

WALTER H. DEICHES.
